ABSTRACT OF THE DISCLOSURE

This patent discloses tube reducing apparatus of the kind in which the tube is successively worked by a plurality of equiangularly spaced circular planetary dies containing tapering die openings. The dies traverse a straight line portion of substantial length while in contact with the work. Pinions associated with the ends of the dies cooperate with an internally toothed endless gear path to insure proper indexing, i.e., to insure that the wider part of the tapering groove in each die first comes into contact with the tube, and at the same time, cam means are provided to cooperate with the dies while they traverse the straight line portion of their travel (while they are in contact with the work) to insure contact between the pinions and the gear path.

This invention relates to tube reducing apparatus, and more particularly to tube reducing apparatus employing a plurality of opposed circular dies for continually reducing the diameter and wall thickness of metal tubing by the application of a cold swaging action.

Opposed circular dies have heretofore been employed for reducing tubing. Each of these dies has a tapering, semicircular, spiral-shaped groove formed in its periphery. The circumferential length of the grooves almost always is less than 180°. When the dies are placed one on top of the other, the grooves define the circular path which contracts when the dies are moved along a linear path and simultaneously rotated in opposite directions; and which enlarges when the direction of travel of the dies is reversed.

Apparatus is available wherein a single pair of the opposed dies is employed for reducing the outer diameter and wall thickness of metal tubing. This pair of dies is reciprocated, that is, moved back and forth, along a linear path of travel having a predetermined length. During the working stroke, the pair of dies is moved in one direction and affects a reduction in the tube size. At the end of the working stroke, the entire die mass is stopped, after which the direction of travel of the dies is reversed so that the dies are moved back toward the starting point. The entire die mass is again stopped at the starting point and the direction of travel reversed. Before the second working stroke, the tubing is advanced incrementally through the apparatus so that a fresh section of tubing is positioned to be reduced.

Tube reducing apparatus of this type performs satisfactorily in reducing tubing. However, apparatus of this type has certain disadvantages which the present invention seeks to overcome.

For example, the dies are actually reducing tubing for only a fraction of each cycle of operation. It would appear on the surface that the work performance of the dies is about 50% of each cycle. However, this is not the case. During the working stroke of each reciprocal cycle of operation, the dies are initially accelerated from a dead stop and thereafter decelerated to a dead stop. During the acceleration and the deceleration of the dies, the rate of work performed, on the average, is less than the rate of work performed by the dies when the dies reach the de-

sired velocity. Hence, during each working stroke, the overall average rate of work performed is less than the rate of work performed by the dies when the dies reach the desired velocity. Furthermore, the return stroke of each operating cycle represents a complete loss in that no work is performed. Still further, the tube cannot be advanced through the apparatus during the return stroke. The tube can only be advanced after the dies have been stopped at the starting point of the working stroke or sufficient stroke provided so that the dies can be rotated to a position where they lose contact with the material being reduced long enough to allow the tube to be advanced before starting its return stroke.

Another disadvantage is that the reversing motion of the dies, subjects the various drive components to undesirable stresses. Consequently, the physical size of this type of apparatus is large in order that the various stresses may be accepted and tolerated.

Still another disadvantage is that tube reducing apparatus of this type must, of necessity, incorporate a reversing drive mechanism. Reversing drive mechanisms are expensive to purchase and operate, as well as being complicated and relatively difficult to maintain.

Accordingly, as an overall object, the present invention seeks to provide tube reducing apparatus which does not have the above described disadvantages.

Another object of the invention is to provide tube reducing apparatus whose production rate is higher than the production rates of any of the tube reducing apparatus heretofore available.

Still another object of the invention is to provide tube reducing apparatus employing rotating dies, wherein a greater percentage of the die circumference is used for reducing tubing.

A further object of the invention is to provide tube reducing apparatus of novel construction wherein the mating, rotating dies move in a single direction and at a constant speed.

A still further object of the invention is to provide tube reducing apparatus employing a plurality of mating, rotating dies all of which move at a constant speed and in a single direction.

Another object of the invention is to provide tube reducing apparatus by which the desired reduction in tube size may be accomplished by each set of mating, rotating dies.

Still another object of the invention is to provide tube reducing apparatus wherein the desired reduction in tube size may be accomplished in multiple steps.

In accordance with the present invention, a tube reducing apparatus is provided comprising a loading conveyor by which tubing is fed along a longitudinally feed axis of the apparatus; a tube reducing mechanism of the invention for reducing the outer diameter and wall thickness of the tubing; and a discharge conveyor by which the reduced tubing is conveyed to storage or to a further processing area. The tube reducing mechanism comprises groups of planetary dies which revolve about separate axes of revolution which are perpendicular to the longitudinal feed axis of the apparatus. Each group of planetary dies is provided with means for guiding the dies thereof along an endless path of travel including a straight path segment positioned adjacent to and parallel with the longitudinal feed axis of the apparatus. The sets of planetary dies are revolved in timed relation about their respective axes of revolution whereby corresponding dies of the groups are brought opposite one another for movement along the straight path segments as a tube reducing die set. Each tube reducing die set causes the desired amount of reduction to be accomplished in a given section of the tubing. As the planetary dies of each tube reducing die set moves along its endless path of travel, rotating

means provided therealong causes the planetary dies to rotate about their central axes at equivalent angular velocities. Hence, at any given moment in the travel of the tube reducing die sets, the planetary dies thereof will have the same orientation. The present tube reducing mechanism also includes a mechanism for rotating the tube about the longitudinal feed axis and for advancing the tube incrementally along the longitudinal feed axis and hence through the apparatus.

As will hereinafter become apparent, the present tube reducing mechanism has two modes of operation. As explained above, each planetary die includes a tapering, arcuate, spiral-shaped groove in its periphery. Consequently, the grooves of all of the tube reducing die sets may be so dimensioned that each tube reducing die set provides the same amount of tube reduction. In this instance, the tube advancing mechanism is operated after the passage of each tube reducing die set. Alternatively, the grooves of each tube reducing die set may be so dimensioned whereby the required amount of tube reduction is accomplished in multiple steps, that is, by a plurality of tube reducing die sets. In this instance, the tube advancing and rotating mechanism would be operated after a given number of the tube reducing die sets have completed their travel along the straight path segment.

The above and other objects and advantages of the present invention will become apparent from the following detailed description by reference to the accompanying drawings, in which:

TUBE REDUCING APPARATUS—GENERAL DESCRIPTION

Referring now to FIGS. 1 and 2, there is shown a tube reducing apparatus indicated generally by the numeral 20. The apparatus 20 includes a feed conveyor 22 which conveys tubing 24 along a longitudinal feed axis 26 of the apparatus 20. The tubing 24 is conveyed into a tube reducing section 28 and thereafter onto a discharge conveyor 30 which accepts and conveys the reduced tubing 24a to a storage section or to a further processing area.

The tube reducing section 28 includes a tube reducing mechanism 32 shown in dotted outline in FIG. 2, which resides within a housing 34. Associated with the tube reducing mechanism 32 is drive means 36 comprising a main drive motor 38 and a gear reducer 40. A pair of drive shafts 42 (only one visible) extends from the gear reducer 40 and is connected to the tube reducing mechanism 32, as will be explained. Also associated with the

tube reducing mechanism 32 is a tube advancing and rotating mechanism 44 (shown in phantom outline) which rotates the tubing 24 about the longitudinal feed axis 26 and also advances the tube incrementally along the longitudinal feed axis 26 and hence through the tube reducing mechanism 32.

As illustrated in dotted outline in FIG. 1, additional tube reducing mechanism 32 may be driven by the drive means 36. Alternatively, separate drive units may be provided for each additional tube reducing mechanism 32.

TUBE REDUCING MECHANISM 32

Referring now to FIGS. 3 and 4, the tube reducing mechanism 32 comprises two planetary die assemblies 46A and 46B which are of identical construction but of different orientation with respect to the longitudinal feed axis 26. Each of the planetary die assemblies 46A and 46B includes groups of planetary dies 48 which revolve about an axis of revolution 50 in opposite directions as indicated by the arrows 52. In the present tube reducing mechanism 32 each group of planetary dies 48 consists of three circular dies 54A, 54B and 54C. The arrangement is such that corresponding circular dies, that is, the dies 54A, the dies 54B and the dies 54C, of the planetary die assemblies 46A and 46B, cooperate as a tube reducing die set during the actual tube reduction operation. As can be seen in FIG. 4, the circular dies 54A of the die assemblies 46A and 46B are positioned opposite each other and cooperate to reduce the tubing 24. As the die assemblies 46A and 46B rotate in opposite directions as indicated by the arrows 52, the circular dies 54B will be positioned opposite each other to form a second tube reducing die set and thereafter the circular dies 54C will be positioned opposite each other to form a third tube reducing die set.

Each of the circular dies 54A—54C are rotatably supported on a carriage 56 having a rod 58 projecting radially toward the axis of revolution 50 and slideably engaged in a cylindrical arm 60 of a yoke 62. The yoke 62 is rigidly secured to a shaft 64 which is rotatably supported in the housing 34. Each of the shafts 64 is, in turn, coupled with and driven by one of the drive shafts 42.

Each of the circular dies 54A, 54B and 54C, the carriages 56 and the associated components thereof are identical in construction. Consequently, the following description of the components associated with the circular die 54A applies equally as well to the circular dies 54B, 54C.

As can best be seen in FIG. 3, the circular die 54A is supported on a shaft 66 which projects outwardly of the carriage 56 and is rotatably supported thereon. Secured at each extreme end of the shaft 66 is a follower 68. Secured to each end of the shaft intermediate of the carriage 56 and the follower 68 is a pinion 70. Hence, the circular die 54A has associated therewith two spaced followers 68 and two spaced pinions 70, all of which are rotatable with the circular die 54A about its central axis 72.

Referring again to FIGS. 3 and 4, each of the followers 68 is engageable in sequence with the inner surfaces of an arcuate cam 74, first and second inclined cams 76, 78 and the exterior surface of a horizontal cam 80. As best shown in FIG. 4, the first and second inclined cams 76, 78 extend tangentially from the opposite ends of arcuate cam 74. The first inclined cam 76 guides the followers 68 into engagement with the horizontal cam 80. As the followers leave the horizontal cam 80 they engage the second inclined cam 78 and are guided thereby to the arcuate cam 74. Accordingly, the followers 68 will be guided by the cams 74, 76, 80 and 78 along an endless path of travel represented by a dash-dot line consisting of an arcuate path portion 74A corresponding to the arcuate shape of the cam 74, to inclined straight path segments 76A and 78A corresponding to the inclined cams 76, 78, and a horizontal straight path segment 80A corresponding to the horizontal cam 80. The arcuate cam 74, the first and second inclined cams 76, 78 and horizontal cam 80 thus comprise means for guiding the circular dies 54A—54C

along an endless path of travel including the straight path segment 80A disposed adjacent to and parallel with the longitudinal feed axis 26 of the apparatus 20. The horizontal cams 80 have a second function, which is maintaining the circular dies engaged with the tubing 24 during reduction of the same.

As stated above, the planetary die assemblies 46A and 46B are rotated in unison and in opposite directions. They are, however, rotated in a timed relation whereby corresponding circular dies are brought opposite one another for movement along the straight path segments 80A as a tube reducing die set. Simultaneous with the revolution of the planetary dies 54 about their respective axes of revolution 50, each of the circular dies is rotated about its central axis 72. To accomplish the rotation of the circular dies, gear means 82 is provided which comprises an arcuate gear segment 84, inclined gear segments 86 which are tangent to the ends of the arcuate gear segment 84 and a horizontal, central straight gear segment 88. The gear means 82 provides means for rotating the corresponding planetary dies of each tube reducing die about their central axis 72 and at equivalent angular velocities. Consequently, at any moment in the movement of the circular dies 54 about the axis of revolution 50, the corresponding dies of each tube reducing die set will have identical orientations.

The overall arrangement of the tube reducing mechanism 32 is such that the planetary dies 54 are simultaneously rotated about their central axis 72 and revolved about their axis of revolution 50 at a constant velocity. Therefore, there is no acceleration or deceleration associated with the movement of the circular dies 54 as in the prior-art apparatus.

Reference is now directed to FIG. 5 wherein the movement of the circular dies 54 is schematically illustrated. The circular dies 54A, comprising the first tube reducing die set, move along the straight path segment 80A from the dotted outline position to the dash-dot outline position designated by 54A'. The planetary die assemblies 46A, 46B will have revolved through an angle indicated at W when the circular dies 54A are at the position indicated by 54A'. Meanwhile, the circular dies 54B move from the dotted outline position to that position illustrated by the dash-dot outline indicated at 54B'. From the position indicated at 54B', the circular dies 54B must move through an angle indicated at I in order to reach the position previously occupied by the circular dies 54A.

It should be evident that the angle W represents the work angle and the angle I represents the idle angle. As can be seen, the work angle W is less than the idle angle I. In one embodiment of the invention, the circular dies 54A-54C were equiangularly spaced at 120° about the axis of revolution 50. The work angle W was about 50° while the idle angle I was equal to about 70°. Consequently, for each one-third of a revolution of the planetary die assemblies 46A and 46B, work is accomplished 42% of the time. Although the 42% figure seems low, it should be remembered that the circular dies 54A-54C are continuously revolved about the axis of revolution 50 at a constant angular velocity rather than being reciprocated as in prior-art devices. Another important advantage which should be evident at this time, is that since the circular dies 54A-54C of the planetary die assemblies 46A and 46B rotate at a constant angular velocity, the present tube reducing mechanism 32 may be connected directly to the gear reducer 40 whose sole function is to reduce the relatively large number of revolutions per minute of the main drive motor 38 to a speed commensurate with the needs of the tube reducing mechanism 32. Consequently, the present tube reducing mechanism 32 does not have and does not require a reversing drive mechanism as does the prior-art tube reducing apparatus described above.

Referring now to FIGS. 6 and 6A, there is illustrated a pair of opposed circular dies each designated generally

by the numeral 54. It is to be understood that the following description applies equally as well to all of the circular dies 54A-54C.

As can be seen, the opposed circular dies 54 rotate in the directions indicated by the arrows 94 and move along the straight path segments 80A in the direction indicated by the arrows 96. As is conventional, each of the circular dies 54 is provided with a semicircular groove 98 extending around a fraction of its periphery. The groove 98 is tapered having the largest diameter at the point 100 and having the smallest diameter at the point 102. Beyond the point 102, that is to the point 104, the diameter of the semicircular groove is constant. Consequently, the overall arrangement is such that when the points 100 of the circular dies 54 are opposite one another, a circular pass of largest diameter is defined. As the circular dies move to the right of FIG. 6, the circular pass formed diminishes in diameter until the points 102 of the circular dies 54 are opposite each other at which time the diameter of the circular pass is at a minimum. Continued rotation of the circular dies 54 to the right of FIG. 6 provides a circular pass of constant diameter corresponding to the circular pass defined by the semicircular groove 98 between the points 102 and 104.

As can be seen, the tubing consists of three regions, namely, the region 24 corresponding to the unreduced tubing supported on the feed end of the apparatus; the reduced end 24a which is at the desired diameter and wall thickness and is supported on the discharge end of the apparatus; and a tapered section 24b whose diameter and wall thickness vary from the point indicated at X to the point indicated at Y. Beyond the point indicated at Y the wall thickness and outer diameter of the tapered section 24b is constant and extends to the point indicated at Z. During rotation of the circular dies, the point 100 thereof will coincide with that point on the tubing indicated at X while the point 102 of the circular dies corresponds to that point on the tapered section 24b indicated at Y. Furthermore, that section of the semicircular groove 98 between the points 102 and 104 of the circular dies corresponds to the region of the reduced end 24a indicated between the points Y and Z. Consequently, between the points X and Y on the tapered section 24b, the tubing is being reduced in outer diameter and in wall thickness. Between the points Y and Z, however, the outer diameter and wall thickness remains constant. The point indicated by Y is known in the art as the sizing point while the region between the points Y and Z is known as the ironing section.

As can be seen, a mandrel 106 is supported within the tapered section 24b of the tubing 24 in the region of the straight path segments 80A. The mandrel 106 is stationary and comprises a tapered portion 108 and a size point 110 extending through and beyond the region defined by the points Y and Z. The tapered portion 108 of the mandrel 106 supports the tubing during its reduction in outer diameter and wall thickness, while the sizing point 110 supports the constant diameter segment (between the points Y and Z) of the tubing so that the reduced section 24a will have the desired outer diameter and wall thickness.

As explained above, the circular dies of prior-art tube reducing apparatus had semicircular grooves whose circumferential length was less than 180°. In one specific example of a prior-art circular die, the working surface of the semicircular groove had a circumferential length of about 118 angular degrees. At each end of the working face of the semicircular groove, there was provided a contour-relief consisting of a semicircular groove having a diameter larger than the unreduced diameter of the tubing. Similarly, at the smallest diameter end of the semicircular groove there was provided a second contour-relief consisting of a semicircular groove whose diameter was larger than the diameter of the reduced tubing. The overall circumferential length of the semicircular groove

including the contour-relief end segments was 180° .

In the present apparatus, the circular dies revolve about their axis of revolution in one direction, for example, the counterclockwise direction illustrated in the drawings. Consequently, the circumferential length of the semicircular grooves 98 may be greater than 180° . Furthermore, no contour-relief segments are necessary. Therefore, a maximum amount of the circumferential length of the circular die may be employed in the actual reduction of tubing. For example, in one embodiment of the present invention, the circumferential length of the semicircular groove 98 between the point 100 and the point 104 consisted of about 200 angular degrees.

It should be evident then that since a greater circumferential length of the circular die may be employed in reducing the tubing, the distance between the points X and Z is greater than the corresponding distance in prior-art tube reducing apparatus. It follows then that for the same reduction in outer diameter, the angle of taper in the present tube reducing apparatus is shallower than the corresponding angle of taper in the prior-art tube reducing apparatus. Therefore, in the present tube reducing apparatus the reduction of the tubing is more easily accomplished than in the prior-art apparatus.

MODE OF OPERATION

Inasmuch as the present tube reducing mechanism 32 employs a plurality of planetary dies, it has many modes of operation. The present tube reducing mechanism has hereinabove been described and illustrated as including three planetary dies for each of the planetary die assemblies 46A, 46B. Consequently, three tube reducing die sets are formed as the planetary dies are revolved about their respective axes of revolution 50.

One mode of operating the present tube reducing mechanism 32 is graphically illustrated in FIG. 7 wherein the tube reducing die sets are indicated by tangent circles designated A, B and C. The graph of FIG. 7 is a plot of the per cent of tube reduction accomplished by each die set versus revolutions of the die assemblies. In this instance, the semicircular grooves of each tube reducing die set A, B and C, is dimensioned so as to provide the same amount of tube reduction. Consequently, as can be seen in FIG. 7, each of the tube reducing die sets A, B and C will provide 100% of the desired tube reduction. Therefore, the tubing may be advanced after each of the tube reducing die sets A, B and C has traversed the straight path segment 80A. Tube advance is indicated in FIG. 7 by the vertical arrows 109. Inasmuch as the circular dies of each tube reducing die set is immediately disengaged from the tubing at the end of the straight path segment 80A, the tube may be advanced automatically immediately after the disengagement. The time required to advance the tubing will, of course, be considerably less than the time required for the second tube reducing die set to traverse through the idle angle I (FIG. 5) and therefore the time involved in advancing the tubing does not add to the total time required for one-third of a revolution of the present tube reducing mechanism 32. Consequently, when the second tube reducing die set is brought into engagement with the tubing, the tubing is already advanced and is in position for the second tube reducing operation.

A second mode of operation is graphically illustrated in FIG. 8, which also is a plot of the percent of tube reduction accomplished by each of the tube reducing die sets revolutions of the die assemblies. As in FIG. 7, each of the tube reducing die sets is indicated by tangent circles indicated by the letters A, B and C while the tube advance points are indicated by the arrows 109. In this instance, the semicircular grooves of the first tube reducing die set A are dimensioned to provide approximately one-third of the desired tube reduction; the semicircular grooves of the second tube reducing die set B are dimensioned to provide approximately two-thirds of the desired tube reduction; and the semicircular grooves of the third tube reducing die set C are dimensioned to pro-

vide 100% of the desired tube reduction. Consequently, and as illustrated in FIG. 8, when the first tube reducing die set A has traversed the straight path segment 80A, the tubing will have been reduced approximately one-third of the desired tube reduction. When the second tube reducing die set B has traversed the straight path segment 80A, the tubing will have been reduced approximately two-thirds of the desired reduction. Finally, when the third tube reducing die set C has traversed the straight path segment 80A, the tubing will have been reduced 100% of the desired tube reduction. Hence, the tubing is reduced in multiple steps. In this instance, the tube is advanced after each complete revolution of the planetary dies about the axis of revolution, as indicated by the arrows 109.

It should be noted at this time that the tube reducing mechanism 32 of the present invention may be provided with more than three planetary dies and therefore modes of operation other than those described are possible. For example, FIG. 9 is a graphic illustration of an alternative embodiment of the present tube reducing mechanism wherein four tube reducing die sets are provided. The tube reducing die sets are illustrated in FIG. 9 as opposed, tangent circles labeled A, B, C and D. The graph of FIG. 9 is similar to the graphs of FIGS. 7 and 8. In this instance, the semicircular groove of the first tube reducing die set A is dimensioned to provide approximately one-half of the desired tube reduction while the semicircular grooves of the second tube reducing die set B are dimensioned to provide 100% of the desired tube reduction. Similarly, the semicircular grooves of the third tube reducing die set C are dimensioned to provide approximately one-half of the desired tube reduction while the semicircular grooves of the fourth tube reducing die set D are dimensioned to provide 100% of the desired tube reduction. Consequently, in the operation of this embodiment the tube will be reduced in multiple steps by the first and second tube reducing die sets A and B, whereupon the tube is advanced as indicated by the arrow 109. Thereafter, a second multiple step reduction is accomplished by the third and fourth tube reducing die sets C and D, whereupon the tube is again advanced. Consequently, after each half revolution of the tube reducing mechanism, the tube is advanced incrementally along the longitudinal feed axis of the apparatus.

TUBE REDUCING MECHANISM—ALTERNATIVE EMBODIMENT

Reference is now directed to FIGS. 10 and 11, wherein an alternative embodiment of the tube reducing mechanism is illustrated. Corresponding numerals will be employed to identify corresponding parts heretofore described.

In this embodiment, a tube reducing mechanism 32' is provided comprising two planetary die assemblies 114A, 114B. Each of the die assemblies 114A, 114B includes groups of planetary dies 48 which revolve about an axis of revolution 50 in the direction indicated by the arrows 52. Each group of planetary dies 48 includes three circular dies 54A, 54B and 54C. Each of the circular dies 54A-54C is rigidly connected to a shaft 66 supported for rotation by a carriage 116 having a rod 118 projecting radially inwardly toward the axis of revolution 50. A drive member 120 is supported for rotation about the axis of revolution 50. The rods 118 are slideably supported on the drive member 120 for movement therewith about the axis 50 and for sliding movement radially thereof. Centrally within the drive member 120 there resides a stationary shaft 122 having a cam 124 rigidly secured thereto. Rotatably supported at the end of each of the rods 118 is a cam follower 126 which engages the periphery of the cam 124.

At each end of the shaft 66, there is secured a pinion 70. The pinion 70, the shaft 66 and the circular die 54 associated therewith are rotatable about the central axis 72 of the circular die. Disposed about the axis of revolution 50 of each of the planetary die assemblies 114A,

114B are two spaced gear means 82 each comprising an arcuate gear segment 84 whose opposite ends terminate in inclined gear segments 85, 86 and a horizontal, central straight gear segment 88 connected to the ends of the inclined gear segments 85, 86. The pinions 70 mesh with the gear means 82.

In this embodiment, the gear means 82 have their straight gear segments 88 resting one on top of the other rather than being staggered as in the embodiment illustrated in FIG. 3. Hence, this embodiment is more compact than is the embodiment illustrated, for example, in FIG. 3.

Connected to each of the drive members 120 is a drive shaft 128 which, in turn, is connected to the gear reducer (not shown here). As can best be seen in FIG. 11, the shafts 122 supporting the cams 124, have one end keyed to a plate member 130 extending between both of the shafts 122 and have their other ends journaled to the drive shafts 128.

In operation, the drive shafts 128 rotate the drive members 120 which, in turn, revolve the planetary dies 54A, 54B and 54C about the axis of revolution 50. The pinions 70 meshing with the gear means 82 provide rotation of the circular dies 54A-54C about their central axis 72. Each of the circular dies 54A-54C traverses an endless path of travel indicated by a dash-dot outline consisting of an arcuate path segment 74A corresponding to the arcuate gear segment 84, inclined path segments 76A, 78A corresponding to the inclined gear segments 85, 86 and a horizontal straight path segment 80A corresponding to the horizontal, central straight gear segment 88.

The shafts 122 supporting the cams 124 are stationary and, therefore, the cams 124 remain in the positions illustrated. The cams 124 have the same general peripheral configuration as the endless path of travel indicated by the dash-dot line described above. However, each of the cams 124 includes a concave cam surface 132 positioned opposite the straight path segments 80A. The contour of each of the concave cam surfaces 132 corresponds to the path of travel of the cam follower 126 as each of the carriages 116 moves from an inclined position when the central axis 72 of the shaft 66 is coincident with a point 134 on the straight path segment 80A to the oppositely inclined position wherein the central axis 72 of the shaft 66 is coincident with a point 136 at the end of the straight path segment 80A. The overall arrangement of this embodiment is such that the circular dies 54A-54C are revolved about their respective axis of revolution 50 while simultaneously being rotated about their central axis 72. Consequently, the corresponding circular dies 54A-54C of each of the planetary die assemblies 114A, 114B are brought sequentially opposite one another for movement along the straight path segments 80A as a tube reducing die set, as described above.

Although the present invention has been shown in connection with certain specific embodiments, it will be readily apparent to those skilled in the art that various changes in form and arrangement of parts may be made to suit requirements without departing from the spirit and scope of the present invention.

I claim as my invention:

1. In apparatus for reducing at least the outer diameter of a tubing, the combination comprising: groups of planetary dies, the planetary dies of each group being equiangularly spaced about an axis of revolution; the axes of revolution of said groups of planetary dies residing in a common plane and being equidistant from a longitudinal feed axis of said apparatus and perpendicular thereto; means for each group of planetary dies for guiding the planetary dies of said groups along separate endless paths of travel about their respective axis of revolution, each of said paths of travel including a straight path segment positioned adjacent to and parallel with said longitudinal feed axis; means for revolving said groups of planetary dies in timed relation about their respective axes of revolution whereby corresponding planetary dies of said groups

are brought opposite one another for simultaneous movement along said straight path segments as a tube reducing die set; means for rotating the corresponding planetary dies of each tube reducing die set about their central axes during movement thereof along said endless paths of travel; and means for rotating and advancing a tube incrementally along said longitudinal axis and hence through said apparatus; a number of said tube reducing die sets being dimensioned to reduce a tube in multiple steps, said tube rotating and advancing means being operable only after the passage of said number of said tube reducing die sets along said straight path segments.

2. In apparatus for reducing tubing, the combination comprising: planetary die assemblies having axes of revolution which are equivalent from a longitudinal feed axis of said apparatus and perpendicular thereto; each of said planetary die assemblies comprising a drive member rotatable about the axis of revolution, a plurality of planetary dies equiangularly spaced about said drive member and hence the axis of revolution, means for connecting said planetary dies to said drive member, means for slideably supporting each of said planetary dies for movement radially of the axis of revolution, at least one endless gear track adjacent to said planetary dies, said endless gear track having a straight segment positioned adjacent to and extending parallel with said longitudinal feed axis, a pinion secured to each of said planetary dies and engaged with said endless gear track, said pinions causing rotation of the planetary dies about their respective central axes during revolution of said planetary dies about the axis of revolution, and cam means for maintaining the pinions engaged with said endless track in said straight segment thereof and comprising a cam member supported at the axis of revolution, and a cam follower associated with each planetary die; means connected to the drive members for revolving said planetary dies in timed relation whereby corresponding planetary dies of said assemblies are brought opposite one another for simultaneous movement along said straight segments as a tube reducing die set; and means for rotating and advancing a tube incrementally along said longitudinal axis and hence through said apparatus.

3. In apparatus for reducing tubing, the combination comprising: planetary die assemblies having axes of revolution which are equidistant from a longitudinal feed axis of said apparatus and perpendicular thereto; each of said planetary die assemblies comprising a drive member supported for rotation about the axis of revolution, a plurality of planetary dies equiangularly spaced about said drive member and hence the axis of revolution, means for connecting each of said planetary dies to said drive member for movement therewith about the axis of revolution, means for slideably connecting each of said planetary dies to said drive member for movement radially of the axis of revolution, spaced, parallel, endless gear tracks each having a straight gear segment disposed adjacent to said longitudinal feed axis and extending parallel therewith, said planetary dies being positioned between said spaced, parallel, endless gear tracks for movement therebetween, a pinion secured to each side of each planetary die, said pinions being engaged with said endless gear tracks whereby revolution of said planetary dies about the axis of revolution causes rotation of the planetary dies about their respective central axes, a cam follower associated with each planetary die and rotatable about the central axis of the die, and at least one straight cam segment inwardly spaced from and parallel to each of the straight gear segments of said endless gear tracks, said straight cam segments being positioned for engagement by the cam followers during movement thereof along the straight gear segments whereby said pinions are maintained engaged with said straight gear segments; means connected to the drive members for revolving said planetary dies about their axes of revolution and in timed relation whereby corresponding planetary dies of said assemblies are brought opposite one another for simul-
